J. B. BEERS.
Ore Amalgamator.

No. 67,842.

Patented Aug. 20, 1867.

Inventor:

J. B. Beers.

United States Patent Office.

JOHN B. BEERS, OF SAN FRANCISCO, CALIFORNIA.

Letters Patent No. 67,842, dated August 20, 1867.

IMPROVEMENT IN AMALGAMATING PRECIOUS METALS.

The Schedule referred to in these Letters Patent and making part of the same.

TO ALL WHOM IT MAY CONCERN:

Be it known that I, JOHN B. BEERS, of the city of San Francisco, San Francisco county, State of California, have invented a new and improved Wire-Gauze Amalgamator; and I do hereby declare the following description and accompanying drawings are sufficient to enable any person skilled in the art or science to which it most nearly appertains to make and use my said invention without further invention or experiment.

The nature of my invention is to provide an amalgamator, so constructed that the particles of gold will be prevented from being carried away before the mercury has taken it up and amalgamated it.

In order to accomplish this object I employ wire-gauze screen, wire cloth, punched, raised, or corrugated copper plates, either amalgamated with mercury, or otherwise, in connection with any of the ordinary devices for the saving of gold or silver. In order to more fully illustrate my invention, reference is had to the accompanying drawings and letters marked thereon, in which—

Figure 1 represents a plan of a sluice or amalgamating-table with my invention attached.

Figure 2, a longitudinal section.

Similar letters indicate like parts in each of the figures.

A is a table or sluice, with the wire gauze B and B' attached, B' being placed slightly above the longer strip B. A corrugated plate, C, is placed transversely across the sluice between the pieces, which forms a riffle at the head of the screen or gauze B. If the gauze is intended for amalgamation it should be made of copper, so that the mercury, while it readily unites with it, will not destroy it. I prefer making the meshes from about one-sixtieth to four sixtieths of an inch square, depending much upon the fineness of the particles of gold and the quantity allowed to accumulate upon its surface.

My invention will be found very useful as a lining for sluices in placer, cement, and quartz mining, and will be efficient in riffle-boxes, shaking-tables, long-toms, rockers, concentrators, the batteries of quartz and auriferous cement-mills, and the covering of the aprons or platforms in front of such batteries, either as a substitute for the copper-amalgamated plates now in use or in connection therewith.

If simply to be used as covering for copper plates, to enable their amalgamated surfaces more effectually to retain the gold, iron-wire screens would answer.

In applying my invention to quartz mining or cement-mills, I line the batteries with the amalgamated copper-wire gauze, of coarse or medium quality. I wind the stump or stem of each stamp with the same material, with a strip of cloth underneath. I place it on a platform in front of the battery, either with cloth or copper plates underlying. I line the sluices from such batteries with a short amalgamated section of the same, and over which I place a shower if the inclination is not sufficient to keep it free from the lodgment of sand and sulphurets.

In applying my invention to hydraulic or placer mining, I line short sections of the sluices with the amalgamated copper-screen wire, underlying it usually with canvas cloth, and protecting the wire surface from contact with large boulders, or very coarse material or debris that might injure it in passing over, by roofing it over with a punched sheet-iron screen, grate-bars, or other device.

For lining a riffle-box it is far superior to a body of mercury contained therein, as the amalgamated screen, when placed upon canvas cloth, and set at a sufficient incline to keep it free from sand, will catch and retain all the gold. At the end of each section of this amalgamated wire I usually place a small riffle or reservoir that will retain any surplus mercury that might escape therefrom.

What I claim as my invention and improvement in amalgamators for amalgamating the precious metals, is—

The use of amalgamated woven-wire gauze or amalgamated perforated sheet metal.

I also claim, in combination with amalgamated wire gauze or perforated sheet metal, the canvas or cloth arranged under the wire gauze or perforated metal.

I also claim, in combination with the amalgamated wire gauze or perforated metal, the use of corrugated amalgamated sheet-metal plates, either with or without the canvas or cloth.

I also claim, in combination with amalgamated plates, the use of iron-wire gauze or screens arranged on or above the plates, substantially as described for the purpose set forth.

In witness whereof I have hereunto set my hand and seal.

J. B. BEERS. [L. S.]
